UNITED STATES PATENT OFFICE.

WILLIAM H. SAUVAGE, OF FLUSHING, NEW YORK, ASSIGNOR TO GOULD COUPLER COMPANY, A CORPORATION OF NEW YORK.

SLACK-ADJUSTER.

1,227,954.

Specification of Letters Patent. Patented May 29, 1917.

Application filed January 25, 1916. Serial No. 74,190.

To all whom it may concern:

Be it known that I, WILLIAM H. SAUVAGE, a citizen of the United States, and resident of Flushing, in the county of Queens and State of New York, have invented certain new and useful Improvements in Slack-Adjusters, of which the following is a specification.

This invention relates to slack adjusters for the brake rigging of railway cars and in its more intense aspect to automatic slack adjuster mechanism associated with the foundation brake rigging beneath the car and preferably adjacent the brake cylinder.

One of the objects of the present invention is to provide a simple and practical slack adjuster adapted to insure predetermined piston travel at all times. A further object is to provide an automatic slack adjuster which will be reliable and efficient in use and operation. A further object is to provide a slack adjuster of the above general type having few parts which will be cheap to manufacture and install. A further object is to provide a slack adjuster of the first above mentioned type which will permit ready readjustment of the parts from time to time as may be necessary.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a perspective view of such parts of the brake rigging as are necessary to fully understand the present invention;

Fig. 2 is a top plan view, partly in section, showing the adjusting mechanism;

Fig. 3 is a side elevation of the parts shown in Fig. 2 with certain parts in section

or broken away to more clearly show the mechanism;

Fig. 4 is a detail perspective view showing the adjusting dog housing.

Referring now to the drawings in detail and more particularly Fig. 1, 5 denotes the brake cylinder provided with an air reservoir 6 and triple valve 7 of well known construction and mounted in the usual manner in suitable supports on the under side of the car. The brake cylinder is provided with a two-part extensible piston 8 connected at its end with a lever 10 of the foundation brake rigging which may be called a live lever. One end of this lever is pivotally connected at 11 to a member 12 leading to the hand brake mechanism while its opposite end is connected to rod 13 leading to the truck brake rigging. A floating lever 14 is provided at the opposite end of the cylinder and is connected intermediate its ends with a corresponding and proportional point on the lever 10 by a tie rod 15. One end of this lever 14 may be considered as being relatively fixed to the adjusting mechanism shown more clearly in Figs. 2 and 3 while its opposite end is pivotally connected to rod 16 leading to the truck brake rigging at the opposite end of the car. These parts with the exception of the adjusting mechanism are all of well known construction and require no detail description. It is however to be noted that the floating lever 14 distinguishes from usual constructions in that it is not connected at one end to the back end of the cylinder. Both ends are free to move as may be necessary to efficiently operate the brakes and take up the excess slack.

The slack adjusting mechanism comprises in its broader aspect an adjusting device adapted temporarily to take up and hold the excess travel during the application of the brakes and on release of the brakes to actuate a permanent take up and holding device to shift the fulcrum point of the lever 14 a distance corresponding exactly to this excess travel. In this manner the piston travel is maintained constant at all times.

The slack adjusting mechanism as herein illustrated comprises an oblong box or casting 20 supported from projecting lugs 21 secured to the car sills and its interior is divided into three chambers, one of which 22, Fig. 2, may be considered the adjusting

chamber, the central one 23 the take up and holding chamber, while the remaining one 24 at the extreme right supports the end of the lever 14 being pivotally connected at 25 with the bifurcated end of a take up and holding rod 26. The pivot pin 25 projects outwardly through slots 27 in the sides of the casing 20 and the head and washer at its opposite ends hold the rod in proper position. A slot 28 is provided on one of the sides through which the dead lever 14 extends as shown more clearly in Fig. 3.

The take up device in chamber 22 comprises a housing 30 shown more clearly in Fig. 4 through which the holding rod 26 passes. A dog 31 is contained in this housing and has its upper end bearing against the fulcrum point 32 and is normally held in canted position by means of a spring 33 coiled about the holding rod. This housing 30 is provided with an upwardly extending ear 34 connected to a pull rod 35 which passes through a lug 36 at one end of the cylinder and has its end connected by means of chain 37 to the lever 10 closely adjacent the point of connection with the brake cylinder piston 8. The upwardly projecting lug 34 of the housing is adapted to travel in a slot 40 and whenever pulled toward the left by excess travel, the dog 31 slides freely along the holding rod 26 but immediately on the release is canted to the position shown by reason of the spring 33 and a second coiled spring 41 within the chamber 22 will on release of the brakes force the housing 30 toward the right against partition 42 separating the chambers 22 and 23. This movement toward the right of the housing 30 will carry the holding rod 26 a distance corresponding exactly to the excess piston travel above that allowed for by the normally slack lost motion chain 37.

In the chamber 23 permanent holding dogs 43 are positioned normally held in canted position by spring 44. The holding rod 26 may pass freely through these dogs to the right but a reactive movement on application of the brakes will be positively prevented.

50 In Fig. 2 there is shown a mechanism for releasing the temporary and permanent holding dogs. This mechanism comprises a lever 50 pivoted on a depending lug 51 and connected near its middle by link 55 to the end of a second lever 52 pivoted to a second depending lug 53. It will be noted that the lever 50 is sufficiently low to be cleared by the dog 31 in its back and forth movement but on movement of the actuating end 60 of the lever 50 to the left its upper end will coact with the dog 31 and move the same to upright position against a stop 54. Motion is transmitted through the link 55 to lever 52 to cause a corresponding movement of 65 permanent holding dogs 43. The right-hand

end wall of the housing 30 is provided with a recess or groove 56 adapted to pass over the stop 54 when movement to the left demands. The chamber 23 is provided with a similar stop 57 in such position as will enable the dogs to move to vertical position and no farther.

The operation of this device is substantially as follows: On application of the brakes the piston cylinder moves outwardly toward the left and motion is transmitted in the usual manner to the several rods and levers to actuate the truck brake rigging. If, however, excess travel takes place or above that allowed by chain 37 the pull rod 35 will move toward the left and carry the housing 30 within the chamber 22 a distance exactly equal to this excess travel, the dog 31 moving freely toward the left along the holding rod 26. On release of the brakes, the spring 41 will cause the housing to return to normal position against the partition 42 and of course will move the rod 26 by reason of the dog 31 a distance corresponding exactly to the excess piston travel, thus causing a corresponding movement of the fulcrum point 25 of the lever 14 and consequently changing the relative position of the foundation brake rigging throughout. The position and location of the dogs 43 will of course prevent a retractive movement of the push rod 26 when the brakes are next applied.

This progressive movement of the holding rod 26 from left to right takes place from time to time as may be necessary, according to the wear of the various parts. When it is necessary to readjust the mechanism as for instance in replacing worn brake shoes, the dogs are tripped by actuation of the lever 50 which, if desired, may be connected by any suitable mechanism to a point at the side of the car to enable this lever to be moved toward the left without requiring the workman to pass beneath the car. On movement of the dogs to vertical position against their respective stops and fulcrums located in upper parts of the chambers, it is, of course, to be understood that the push rod 26 may be moved freely back to original position.

It is thus seen that this invention provides a simple and practical device particularly adapted for use with the brake rigging associated with the under side of the car adjacent the brake cylinder. The device is believed to be reliable and efficient in use and operation at all times and in short is adapted to accomplish, among others, all of the objects and advantages above set forth.

Without further analysis, the foregoing will so fully reveal the gist of this invention that others can by applying current knowledge readily adapt it for various ap-

plications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. In a slack adjuster, in combination, a brake cylinder, a live lever connected therewith, a floating lever, a tie rod connecting said levers, and take up and holding mechanism associated with the fulcrum of the floating lever, said mechanism comprising a casing divided into a plurality of chambers, an adjusting take up device in one of said chambers, a holding device in another, and an adjustable fulcrum for the floating lever in another chamber.
2. In a slack adjuster, in combination, a brake cylinder, a lever actuated thereby, and take up and holding mechanism associated with the fulcrum of said lever, said mechanism comprising a casing divided into a plurality of chambers, a take up device in one of said chambers, a holding device in another, an adjustable fulcrum for the lever in another chamber, and a take up and holding rod pivotally connected with the end of the lever and passing through all of said chambers.
3. In a slack adjuster, in combination, a brake cylinder having a piston, a live lever pivotally connected with said piston, a floating lever connected with said first mentioned lever and actuated thereby, and take up and holding means associated with one end of said floating lever comprising a casing, a take up and holding rod within said casing and pivotally connected with the end of said floating lever, a clutch connected with the piston adapted to slide along said holding rod on excess piston travel and engage and move the holding rod a distance corresponding thereto on release of the brakes to shift the fulcrum of said floating lever, and means for holding said parts in shifted position.
4. In a slack adjuster, in combination, a brake cylinder having a piston, a live lever connected therewith, a floating lever at the opposite end of the cylinder, a link connecting said levers intermediate their ends, and take up and holding mechanism associated with the fulcrum of said floating lever comprising a casing supported from the under side of the car body, a take up and holding rod within the casing and pivotally connected with the end of said floating lever, means adapted to move along said holding rod on excess piston travel and move said holding rod a distance corresponding to the excess travel on release of the brakes to shift the fulcrum of said floating lever,

and means for holding said fulcrum in shifted position comprising a holding dog coacting with said push rod and casing and normally spring held in biting engagement with said rod.

5. In a slack adjuster, in combination, a brake cylinder, a lever connected therewith, and take up and holding mechanisms associated with said lever, comprising a holding rod connected with said lever, a slideable member coacting with said rod and having a connection with the brake cylinder piston, a dog within said housing normally held in canted position adapted to move freely in one direction on application of the brakes when involving excess piston travel and bite into the rod on release of the brakes and carry the same in the opposite direction a distance equal to the excess piston travel, and means adapted to hold 75 said rod in its newly adjusted position.

6. In a slack adjuster, in combination, a brake cylinder, a lever connected therewith, and take up and holding mechanisms associated with said lever, comprising a casing, 90 a holding rod connected with said lever and disposed longitudinally within said casing, a slideable housing in said casing and coacting with said rod and having a connection with the brake cylinder piston, gripping 95 means within said housing adapted to move freely in one direction on application of the brakes involving excess piston travel and bite into the rod on release of the brakes to carry the same in the opposite direction 100 a distance equal to the excess piston travel, and means adapted to hold said rod in its newly adjusted position, comprising a plurality of gripping means mounted in said casing and normally held in position to engage and hold said rod.

7. In a slack adjuster, in combination, a brake cylinder, a lever connected therewith, and take up and holding mechanisms associated with said lever, comprising a casing, 110 a holding rod connected with said lever and disposed longitudinally within said casing, a slideable housing in said casing and coacting with said rod and having a connection with the brake cylinder piston, a dog within 115 said housing normally held in canted position adapted to move freely in one direction on application of the brakes when involving excess piston travel and bite into the rod on release of the brakes and carry the same in the opposite direction a distance equal to the excess piston travel, and means adapted to hold said rod in its newly adjusted position 120 comprising a dog coacting with the rod and a spiral spring about said rod engaging the dog to hold the same in biting engagement therewith.

8. In a slack adjuster, in combination, a brake cylinder, a live lever connected therewith, a floating lever, a tie rod connecting 130

the levers, and take up and holding mechanisms associated with the fulcrum of the floating lever, comprising a casing, a holding rod connected with said floating lever 5 and disposed longitudinally within said casing, a slideable housing in said casing and coacting with said rod and having a connection with the live lever adjacent the point of connection with the brake cylinder piston 10 ton, a dog within said housing normally held in canted position adapted to move freely in one direction on application of the brakes when involving excess piston travel and bite into the rod on release of the brakes 15 and carry the same in the opposite direction a distance equal to the excess piston travel, and means adapted to hold said rod in its newly adjusted position comprising a dog coacting with the rod and a spiral spring 20 about the rod engaging the dog to hold the same in biting engagement therewith, and means mounted on the casing adapted to coact with both of said dogs to move them to release position.

Copies of this patent may be obtained for five cents each, by addressing the "Commissioner of Patents, Washington, D. C."

9. In a slack adjuster, in combination, a lever to which one end of said slack adjuster is connected and adapted to form a movable support therefor, said adjuster including a rod having temporary and permanent take up and holding dogs and a single means 30 adapted to release both of said dogs to permit a relative movement of the rod with respect thereto.

10. In a slack adjuster, in combination, a cylinder, a lever connected with the piston 35 thereof, a floating lever, a tie rod connecting said levers, said adjuster constituting a movable support for one end of said floating lever and comprising permanent holding dogs, and temporary adjusting dogs and 40 a single means for releasing both of said dogs to permit a relative movement of the movable support for said floating lever.

Signed at New York in the county of New York and State of New York this 16th 45 day of December A. D. 1915.

WILLIAM H. SAUVAGE.
